UNITED STATES PATENT OFFICE.

FRANCIS W. DRAPER, OF RICHMOND, INDIANA, ASSIGNEE TO STARR PIANO COMPANY, OF RICHMOND, INDIANA, A CORPORATION OF INDIANA.

SHEET-DRIVING MECHANISM FOR AUTOMATIC PLAYERS

1,071,897.

Specification of Letters Patent. Patented Sept. 2, 1913.

Original application filed August 24, 1910, Serial No. 578,780. Divided and this application filed March 23, 1911. Serial No. 616,348.

To all whom it may concern:

Be it known that I, FRANCIS W. DRAPER, a citizen of the United States, residing at Richmond, in the county of Wayne and State of Indiana, have invented a new and useful Sheet-Driving Mechanism for Automatic Players, of which the following is a specification.

The object of my invention is to provide a mechanism by means of which the music sheet may be driven, preferably at a high rate of speed, in a forward direction without the actuation of the sound producing mechanism, the construction being such that portions of any music sheet may be rapidly skipped.

The accompanying drawings illustrate my invention.

Figure 1 is a perspective view of a player piano constructed in accordance with my invention; Fig. 2 a vertical medial section through the expression box, and Fig. 3 a section on line 3—3 of Fig. 2.

In the drawings, 10 indicates the usual inclosing casing of the piano provided with the usual scale rib 11 and strings 12, action 13 and finger keys 14. The pneumatic actions (preferably comprising primary, secondary, and power pneumatics,) act upon the piano actions 13 in any desired manner and are arranged in several horizontal series carried by transverse action trunks 15, these several trunks being connected at their opposite ends to vertical wind trunks 16—16 which, at their tops, are connected through openings 17—17 with a main transverse wind trunk 18. These several parts are firmly, though detachably connected together to form a unitary structure, the parts of which may be disassembled only by first removing the structure as a whole from the piano casing. Each of the vertical trunks 16 is provided with an outwardly projecting ledge 19 adapted to rest upon the upper edge 45 of the side rail 21 of the casing 10. The bottom board 22 of trunk 18 is transversely pierced by a plurality of passages 23, one for each tracker board opening, and mounted in opposite ends of each passage 23 are two nipples 24 and 25. Each nipple 24 is connected by a tube 26, which may conveniently be flexible as usual, with an opening in the tracker board 27, and each nipple 25 is connected by a tube 28 with a similar nipple 29 which leads to the pouch of the primary pneumatic.

Mounted upon the top of the main transverse wind trunk 18, at about its middle, is the open faced box 31 which carries the tracker board 27 and the associated sheet winding rolls, said associated sheet winding rolls being driven in a well known manner, in either direction, by means of a wind motor 32 which is also supported upon the top of the wind trunk 18 and connected to the sheet driving roll by reversing gearing of any well known form controlled by a shifting lever or other controlling member 33. The main wind trunk 34 of the motor is connected by a readily detachable flexible connection 35 with the main chamber 36 of the wind trunk 18. Mounted upon the opposite end of the top of wind trunk 18 is the controller box 41, one side of which is closed by a readily removable cover board 42. Mounted upon the rear of box 41 is a base controller 43, a treble controller 44, a motor controller 45 and an action rail controller 46. Arranged within box 41 are partitions 47, 48, 49, 50, 51, 52 and 53 which divide the interior of said box to form a chamber 54, a main controller chamber 55, a bass passage 56, a treble passage 57, an intermediate passage 58 and a motor controlling chamber 59. The main passage 121 leads from the main chamber 54 of box 41 and is connected by a pipe 122 which is readily detachable from a fitting 123 connected by a pipe 124 with the vacuum chamber 125, the vacuum in which is maintained by the usual pedals 126, and bellows not shown. Leading through partition 48 and forming the only communication between the main chamber 54 and chamber 55, is a passage 127 which may be opened or closed by a valve 128 carried by a valve rod 129 reciprocably mounted in the box 41, and in the present instance, passing through chambers 55 and 59. Valve 128 is slidably mounted upon rod 129 and is normally yieldingly urged against an adjustable nut 131 by means of a spring 132, the tension of which may be adjusted by a nut 133. The nuts 131 and 133 are mounted upon suitably formed threads on rod 129, the arrangement being such that the rod 129 may have a limited play through the valve 128 after said valve has been brought into position to close passage 127. Leading

through partition 51 and forming a direct connection between the main chamber of box 41 and the motor chamber 59, is a passage 135 which may be opened and closed by the 5 reroll valve 136 connected by a suitable rider 137 with rod 129, this valve being so arranged that it will close passage 135 when valve 128 is away from passage 127. Leading from the chamber 54 of box 41 into the 10 interior of the motor controller 45 is a passage 138, the size of which may be controlled by a valve 139 connected to the movable member of the controller 45, as clearly shown in Fig. 3. This movable member of 15 the controller 45 is moved in one direction by means of a spring 64 which is carried by an adjustable stem 65. Leading from the interior of controller 45 into the chamber 59 is a passage 141 which is preferably of the 20 form shown in dotted lines in Fig. 2, the initial end being comparatively wide and short and having a continuation which is comparatively narrow and gradually widens throughout its length. Mounted within 25 chamber 59 so as to cover the pressure side of passage 141 is a motor-controlling valve 142 which is keyed to a rock shaft 143 journaled in suitable bearings in the cover board 42 and in the rear board of box 41, the last 30 mentioned mounting being readily longitudinally separable, as shown in Fig. 3, so that the shaft 143 will be withdrawn with the cover 42. Valve 142 has a slight longitudinal play upon the rock shaft 143 and is 35 yieldingly urged to a seat against the pressure side of passage 141 by means of a light spring 144. The outer end of shaft 143 is projected beyond the outer face of cover 42 and secured to this projected end is a lever 40 145 by means of which the valve 142 may be adjusted relative to passage 141 and thus control the velocity of air which may be drawn at any particular time by the bellows from the motor so as to thus control the 45 speed of the motor.

Lever 145 is connected by a link 146 to a lever 147 connected in any suitable and common manner with a controlling lever 148 which is arranged at the front of the 50 key bed and this link 146 is connected with the rod 149 slidably mounted in suitable bearings as shown in Fig. 1 and provided with a pointer 151 arranged to traverse a tempo scale 152 mounted within sight with 55 in the tracker board box 31. Rod 129 is projected through one of the end boards of box 41 as clearly shown in Figs. 1 and 2, and to this projected end is secured an arm 153 which is connected to a rod 154 slidably mounted in suitable bearings on the front of the upper wind trunk 18 and this rod is connected by a lever 155 and any ordinary and usual intermediate connections 60 with a roll controlling lever 156 mounted 65 at the front of the key board. Rod 154 car-

ries a pair of separated collars 157 and 158 and between which the driving gear controlling lever 33 is extended, the said collars being sufficiently separated so that valves 128 and 136 may be moved from 70 open to closed position and vice versa without causing any action of lever 33, which serves to reverse the action of the motor on the music sheet. The passage 165 forms the communication between chamber 36 of 75 trunk 18 and the motor chamber 59 of box 41.

With the parts in the position shown in the drawings, the operation so far as the sheet driving mechanism is concerned, is as 80 follows: The reroll valve 136 is over opening 135 and the lever 33 is therefore in such position as to connect the motor with the sheet winding mechanism in such way as to drive the same forward. In order to start 85 the motor, the operator will shift lever 148 to the left thus swinging lever 145 so as to swing valve 142 to the right in Fig. 2. This will open opening 141 to a greater or lesser extent and the air from the motor will have 90 to pass through this opening into the motor controller 45 and thence through passage 138 into chamber 54 and from thence to the bellows, the speed of the motor being determined by the position of valve 142, and 95 the controller 45 opening and closing the valve 138 automatically to compensate for differences in vacuum produced by the bellows, in the usual manner.

It is often desirable to skip portions of a 100 perforated music sheet and it has heretofore been proposed to make such skipping possible by providing a cover for the tracker board so as to prevent ingress of air as the perforated portions of the music sheet pass 105 over the tracker board, but such an arrangement is objectionable because of the clumsy appearance of the cover and because of the improper wear upon the music sheet. In order to accomplish this result, therefore, 110 the collars 157 and 158 on rod 154 are spaced far enough apart to permit a closing of valve 128 and an opening of valve 136 without any movement of lever 33 when it is in position to produce forward movement 115 of the sheet driving mechanism. By this arrangement further exhaustion of air from the pneumatic action trunks is prevented and a direct connection is made between the bellows and motor, thus cutting out or 120 short-circuiting the motor controller 45 so as to drive the motor ahead at full speed, and consequently drive the music sheet ahead at full speed but, there being no suction upon the primary valve chambers 125 which communicate with the tracker board, there will, of course, be no actuation of the pneumatic action. This position of parts is obtained by an intermediate position of the reroll lever 156. Further movement 130

of the lever in reroll direction brings collar 157 into engagement with lever 33 so as to reverse the driving train, the spring 132 permitting this action of rod 129 while valve 128 is kept closed over passage 127.

5 Certain of the features shown but not claimed in this application are claimed in Patent No. 1,016,917, granted to me on February 6, 1912, on application Serial No. 10 578,780, filed August 24, 1910, and Patent No. 1,021,305, granted to me on March 26, 1912, on application Serial No. 616,349, filed March 23, 1911, of the former of which applications the present application is a division.

15 I claim as my invention:

1. In a player mechanism, a bellows, a pneumatic motor, sheet-supporting mechanism, a driving train between the motor 20 and sheet-supporting mechanism, a reversing member for reversing the connections between the motor and the sheet-supporting mechanism, a connection between the motor and bellows, a valve controlling said connection, a pneumatic action, a connection between said pneumatic action and bellows, a valve for controlling said connection, a valve stem controlling both of said valves, a spring connection between one of said 25 valves and the valve stem whereby the stem may move independently of the spring-connected valve, and a connection between said

valve stem and reversing member of the driving train, said connection having a limited play relative to the reversing member whereby the valves may be opened and closed with or without actuation of the reversing member.

2. In a player mechanism a bellows, a pneumatic motor, sheet-supporting mechanism, a driving train between the motor and sheet-supporting mechanism, a reversing member for reversing the connections between the motor and the sheet-supporting mechanism, a connection between the motor and bellows, a valve controlling said connection, a pneumatic action, a connection between said pneumatic action and bellows, a valve for controlling said connection, a valve stem controlling both of said valves, a spring connection between one of said valves and the valve stem whereby the stem may move independently of the spring-connected valve, and a connection between said valve stem and reversing member of the driving train.

35 In witness whereof, I have hereunto set my hand and seal at Richmond, Indiana, this 18th day of March, A. D. one thousand nine hundred and eleven.

FRANCIS W. DRAPER. [L. S.]
